Oscar Geier

UNITED STATES PATENT OFFICE.

BOLESLAW TOMASZEWCZ, OF FLINT, MICHIGAN.

RAILROAD-JOINT.

1,290,411.

Specification of Letters Patent.

Patented Jan. 7, 1919.

Application filed December 30, 1916. Serial No. 139,957.

To all whom it may concern:

Be it known that I, BOLESLAW TOMASZEWCZ, a subject of the Czar of Russia, resident of Flint, county of Genesee, and State 5 of Michigan, have invented certain new and useful Improvements in Railroad-Joints, of which the following is a specification.

This invention relates to improvements in rail joint connections, and has as its principal object the provision of means whereby the abutting ends of the rails may be positively and rigidly secured against longitudinal or lateral movement and without the use of bolts or other clamping means.

Another object is to provide means whereby the joints are materially strengthened and by which the use of joint plates or similar separate securing elements is avoided.

These and other objects are attained by 20 the novel construction and combination of parts hereafter described and shown in the accompanying drawings, forming a material part of this disclosure, and in which:—

Figure 1 is a side elevational view of the device according to the present invention.

Fig. 2 is a vertical sectional view taken on line 2—2 of Fig. 3.

Fig. 3 shows the connection used between abutting rails in cross-section, and

Fig. 4 is a partial top plan view and section showing the connection between two rails.

As illustrated, the rail consists of a base 10, web or stem 11 and head 12, and is provided with a short tenon or extending member 20 having lateral projections 21 protruding from each side.

The connecting element is formed with a

head 25, base flange 26, and central or body portion 27, the same being uniformly thick 40 with the head 25 and having recesses 28 at both ends extending centrally inward from the ends and below the head portion of the rail.

Extending outward laterally from the recesses 28 are cavities 30 so formed and located as to receive the projections 21 whereby the rail ends are held positively within the connection and against longitudinal movement in either direction, as will be best 50 seen in Fig. 4. This connection is of such length as to act as an insert between adjacent rails, and is provided with openings 32 to receive ordinary track spikes such as are used to secure the rails in position.

Having thus described my invention, what I claim as new, and desire to secure by Letters Patent, is:—

The combination with the meeting ends of a pair of rails said rails being spaced 60 apart, the connecting webs of said rails being extended beyond the ends thereof, lugs formed upon the opposite sides of said connecting webs equally distant from the ends thereof, a connecting member for said rails 65 said connecting member having slots in the ends thereof, opening through the under side thereof and offset at the opposite ends, adapted to receive said lugs whereby the rails will be held in their spaced relation 70 substantially as and for the purposes set forth.

In testimony whereof I have affixed my signature this 18th day of November, 1916.

BOLESLAW TOMASZEWCZ.
